LAMP

George Sperti, Covington, Ky., assignor to Sperti
Lamp Corporation, New York, N. Y., a corpora-
tion of Delaware

Application January 15, 1932, Serial No. 586,852

9 Claims. (Cl. 176—1)

This invention relates to electric lamps of the type combining an incandescent filament as a source of visible radiation and an arc constituting a source of visible and ultraviolet radiation.

5 In my prior application for United States Letters Patent, Serial No. 510,412, filed January 22, 1931, there is disclosed a lamp comprising a bulb in which are positioned a pair of spaced electrodes for establishing and maintaining an arc, 10 and an inner bulb in which is an incandescent filament, the filament and arc electrodes being suitably connected across the terminals of the lamp so as to constitute a unitary light source which may be screwed into the ordinary light 15 socket. In my prior application for United States Letters Patent, Serial No. 572,394, filed October 31, 1931, there is disclosed a lamp wherein the incandescent filament is located in the outer bulb and the arc electrodes are positioned in an inner 20 bulb. The separate enclosure of the arc and of the incandescent filament in either case permits the operation of these two sources substantially independently as regards conditions such as vapor or gas pressure and prevents the arc striking to the filament. The circuits in these lamps 25 each comprise an incandescent filament which is in series with the arc between the two electrodes and an incandescent filament or filaments in parallel with the arc electrodes, the latter filament 30 or filaments including means for heating the electrodes for starting and maintaining the arc. Either or both of these filaments may constitute sources of visible radiation, and the series filaments acts as a ballast for the arc current. 35 When current is first supplied to a lamp of this kind, there is a short period before the arc strikes during which the series filament and parallel filament constitute an ordinary series circuit through the lamp, but as soon as the arc strikes, 40 the resistance in the arc path tends to decrease to a low value and hence the current through the parallel filament tends to decrease. The voltage across the arc drops simultaneously and the current through the series filament tends to increase. 45 Where the parallel filament is relied on as a source of visible radiation, it is necessary to provide means in series with the arc to limit the arc current after the arc strikes in order to maintain the parallel filament at incandescence. 50 Where the series filament is relied on as a source of visible radiation and the parallel filament is employed principally for heating the arc electrodes during starting, it is necessary to proportion the series filament so that it will carry the 55 total current through the lamp during normal

operation and will operate at high lighting efficiency and high temperature. During the initial period before the arc strikes, however, the current through the series filament is less than the current during normal operation and hence the 5 tendency is for this series filament to burn only dimly until after the arc strikes. If the series filament is proportioned to burn brightly before the arc strikes, it tends to burn out when the current increases due to the decrease of the resistance of the arc path. On the other hand, if additional ballast resistance is placed in series with this filament so as to limit the arc current, the effect is to decrease the voltage across the 10 parallel filament and hence to decrease the voltage 15 which is available for causing the arc to strike, and also to decrease the lighting efficiency 20 of the incandescent filament.

One object of this invention is to provide a lamp of the class described wherein the incandescent filament may be operated at high lighting efficiency both before and after the arc strikes without danger of burning out the filament. 25

Another object is to provide a lamp of the type described with novel means for controlling and 30 limiting the arc current without in any way affecting the operation of the lamp for arc starting purposes.

Several embodiments of the invention have been illustrated in the accompanying drawings, 35 but it is to be expressly understood that said drawings are for purposes of illustration only and are not to be construed as a definition of the limits of the invention, reference being had to the appended claims for this purpose.

In the drawings,
Fig. 1 is a perspective view of a lamp embodying the invention;

Fig. 2 is a sectional view of a portion of another lamp embodying the invention;

Fig. 3 is a sectional view of a portion of a still further form of lamp embodying the invention;

Fig. 4 is a sectional view of a portion of another lamp embodying the invention; and

Figs. 5 to 8, inclusive, are respectively wiring 45 diagrams of the lamps shown in Figs. 1 to 4 inclusive.

Fig. 1 shows a lamp of the same general type as that disclosed in the aforesaid application for patent, No. 572,394. This lamp comprises an 50 outer bulb 1 of any suitable type, size and shape which is supported by the usual or any suitable base 2. Within the neck of the bulb 1 is sealed a stem or standard 3 which constitutes the usual means for introducing conductors 4 and 5 into 55

the bulb and for supporting the various elements within the bulb. An incandescent filament 6, preferably of tungsten, is supported within the bulb 1 by means of supporting wires 7 and 8 which are fused in the stem 3, the wire 7 constituting a connection between the conductor 4 and one end of the filament 6. Said filament may also be supported by one or more wires 9 secured to a bead 10 formed on the upper end 10 of an inner bulb 11 which is mounted in the lamp by means of a supporting band 12 and supports 13 and 14 that are fused in the stem 3. The inner bulb 11 encloses a pair of electrodes 15 and 16 of any suitable type, said electrodes being mounted in the inner bulb by supports 17 and 18.

The incandescent filament 6 in the outer bulb constitutes a source of visible radiation, and the arc electrodes 15, 16 establish an arc in the inner bulb 11 in an atmosphere of mercury vapor or other suitable gas or vapor, the resultant spectrum of the lamp being a combination of the radiation from the filament and the arc. Preferably the outer bulb 1 is of suitable material which transmits ultra-violet light, and the inner bulb 11 is of material which transmits ultra-violet light of wave lengths longer than a predetermined limit, preferably in the neighborhood of 2600 to 2900 Angstrom units. The light from such a lamp closely resembles natural sunlight 20 in character and quality both as regards the visible part of the spectrum and as regards the invisible ultra-violet part of the spectrum. It will be understood, however, that the construction of the lamp as thus far described constitutes 25 no part per se of the present invention but is shown merely for purposes of illustrating the application of the invention to a practical form 30 of lamp.

The filament 6 constitutes the series filament referred to above which in this case is relied on principally as a source of visible radiation, the parallel filaments being employed primarily for the purpose of heating the electrodes 15 and 16. As pointed out above, one end of the filament 6 is connected to the conductor 4, and as shown in Fig. 1 the other end of said filament is connected by a wire 19 with a heating filament 20 disposed within the electrode 16, said heating filament being connected by a wire 21 with a second 40 heating filament 22 positioned within the electrode 15. Wire 21 may if desired include a resistance 23. The other end of the heating filament 22 is connected by a wire 24 with the support 13 and the support 13 is connected with the conductor 5. The heating filaments 20 and 22, and the resistance 23 if employed, constitute a circuit in parallel with the arc electrodes 15, 16 and the potential drop through this circuit is applied across 50 the electrodes for establishing and maintaining the arc. To this end the wire 19 is connected to the support 18 of the electrode 16 and the wire 24 is connected with the support 17 of the electrode 15, these connections including resistances 25 and 26, the function of which will be described 55 hereinafter.

The operation of the lamp circuit will be described with reference to Fig. 5. When current is first supplied to the lamp, it passes in series through the filament 6, heating filament 20, resistance 23, and heating filament 22. The filament 6 immediately heats up to incandescence, and the heating filaments 20 and 22 heat the electrodes 15 and 16. During the period before the arc strikes, the filaments 6, 20 and 22 and 70 the resistance 23 constitute a series circuit con-

nected across the conductors 4 and 5, a considerable part of the voltage drop being in the circuit in parallel with the electrodes which includes the heating filaments 20 and 22 and the resistance 23. This parallel circuit is proportioned to provide the proper amount of heat for the electrodes and also to provide the desired voltage across the electrodes for starting the arc, the resistance 23 being employed if necessary. As soon as the arc strikes, the resistance 10 of the arc path between the electrodes 15 and 16 is greatly decreased and most of the current flows through the arc, the current through the parallel heating filament circuit being greatly decreased and the voltage drop thereacross being 15 also decreased. The tendency therefore is for the current through the series filament 6 to increase.

Heretofore it has been necessary to proportion the filament 6 so that its lighting efficiency is 20 high on the increased current after the arc strikes and hence said filament has not operated efficiently during the short period before the arc strikes. At the same time it has not been practicable to insert additional resistance in series 25 with the filament 6 because such resistance would have decreased the voltage drop through the parallel heating circuit and hence would have decreased the starting voltage applied to the arc, and also would have decreased the lighting 30 efficiency of the filament 6. In accordance with the present invention, the resistances 25 and 26 are employed to limit the arc current. During the period before the arc strikes, no current flows through these resistances since they are 35 in the leads to the electrodes 15 and 16 and hence said resistances do not affect in any way the operation of the circuit for heating the electrodes and starting the arc. After the arc strikes, the resistances 25 and 26 act to limit the current 40 through the arc and hence to prevent or limit an increase of current through the filament 6. Accordingly, the filament 6 may be proportioned to have high lighting efficiency both during the initial starting period and during normal operation 45 of the lamp. At the same time the characteristics of the circuit which are desired for starting the arc are not affected.

Fig. 2 shows another form of lamp wherein the arc electrodes are placed side by side instead of end to end as in Fig. 1. In Fig. 2, the bulb 27, base 28 and stem or standard 29 may be as described in connection with Fig. 1. The lamp is provided with the usual conductors 30 and 31 which are sealed in the lamp base, and the stem 29 carries supporting wires 32 and 33 for an incandescent filament 34, the latter being also supported by wires 35 secured to the inner bulb 36. A supporting band 37 and supports 38 and 39 serve to mount the bulb 36 on the stem 29, and a stem or standard 40 sealed in the neck of the inner bulb 36 serves to support a pair of electrodes 41 and 42 carried by supporting wires 43 and 44. Preferably the electrodes 41, 42 have the form of tubes of suitable material such as 55 nickel which are partially or entirely coated with one or more oxides of strontium, barium, thorium, etc., to aid in starting the arc. Said electrodes may also be protected by suitable grids 60 or wire coils indicated at 45 and 46.

The lamp circuit of this lamp is shown more clearly in Fig. 6. The filament 34 is connected in series with heating filaments 47 and 48 positioned within the electrode tubes 41 and 42 as 70 75

shown more clearly in Fig. 2. These heating filaments constitute a parallel circuit and the voltage drop through this circuit is applied to the electrodes by suitable connections including resistances 49 and 50. The operation of this lamp is substantially the same as the operation of the lamp shown in Figs. 1 and 5.

A still further form of lamp is illustrated in Figs. 3 and 7. As shown in Fig. 3, said lamp comprises a bulb 51, base 52, stem 53, and conductors 54 and 55. An incandescent filament 56 is supported in the bulb by means of wires 57 and 58 fused in the stem 53 and also by means of wires 59 carried by the inner bulb 60 which is in turn supported on the stem 53 by means of a band 61 and supports 62 and 63. Within the inner bulb 60 is a single electrode element having the form described and claimed in the co-pending application of George Sperti, Serial No. 586,851, which issued May 1, 1934, as Patent No. 1,956,598. This element comprises a body 64 of insulating material such as magnesium oxide having electrode sleeves 65 and 66 secured on its opposite ends. The electrode element is mounted in the inner bulb by means of a supporting band 67 and supports 68 and 69 and is provided with a plurality of passages 70 through which the heating filaments and connecting wires pass.

The lamp circuit is shown more clearly in Fig. 7. The incandescent filament 56 is in series with heating filaments 71 and 72 which as shown in Fig. 3 are positioned in the outer passages 70 and serve to heat both of the electrode sleeves 65 and 66. The voltage drop through these heating filaments is applied to the electrodes, the electrode 66 being connected by a wire 73 with one end of the filament 56 and the electrode 65 being connected by a wire 74 and resistance 75 with the conductor 55. As shown in Fig. 3, resistance 75 is enclosed in the central passage 70. The operation of this circuit will be understood from the foregoing description of Figs. 5 and 6, the single resistance 75 being in series with the arc current and serving to limit the same in the same way as the resistances 25 and 26 of Figure 5.

Fig. 4 shows another form of lamp wherein the series filament is eliminated and the parallel filament is relied on both to heat the electrodes and to provide a source of visible radiation. This lamp comprises as shown an outer bulb 76, base 77, stem 78 and conductors 79 and 80. An incandescent filament 81 is mounted in the bulb in the usual manner, said filament being supported by wires 82 and 83 fused in the stem 78 and by wires 84 carried by the inner bulb 85 which is mounted on the stem 78 as described above. Within the inner bulb is a pair of electrodes 86 and 87 which as shown have the form of tubes closed at one end and supported by wires 88 and 89. These electrodes are heated by filaments 90 and 91.

Referring now to Fig. 8, the filament 81 and the heating filaments 90 and 91 are connected in series across the conductors 79 and 80 and constitute a circuit in parallel with the arc electrodes 86 and 87. When current is supplied to the lamp, these filaments heat up, filament 81 constituting an incandescent source and filaments 90 and 91 heating the electrodes 86 and 87. In this instance the entire voltage drop across the lamp is applied to the electrodes 86 and 87. As soon as the arc strikes, current flows in parallel with the filament 81 by way of the wire 92, resistance 93, electrodes 86 and 87, resistance 94 and wire 95. The arc current however, is limited

by the resistances 93 and 94 to a suitable value and there is substantially no drop in the current flowing through the filament 81 so that the operation of said filament 81 as an incandescent source of visible radiation is not interfered with. 5

It will be seen that the invention provides means whereby the incandescent filament may be operated at high lighting efficiency both before and after the arc strikes without danger of burning out the filament due to the current-limiting effect of the resistances connected in series with the arc. At the same time this result is accomplished without in any way affecting the characteristics of the arc circuit for purposes of starting the arc. Thus the circuit may be designed 15 to provide the proper amount of heat for the electrodes and potential drop across the electrodes in that portion of the circuit which is in parallel with the electrodes and the incandescent filament may be proportioned to operate efficiently 20 without regard to the change in conditions when the arc strikes as explained above. The resistances in series with the arc may if desired be light-emitting filaments and to this end may be placed in any desired location within the lamp. 25 For example, the resistances 25 and 26 of Fig. 1 may be so positioned as to emit visible radiations after the arc strikes and the same is true of the lamps shown in Figs. 2, 3 and 4. It will therefore be understood that the arrangement of the various elements within the lamp may be varied according to the effects which are desired. Also the arc electrodes may if desired be placed in the outer chamber and the incandescent filament or filaments may be placed in an inner chamber as 35 disclosed in the aforesaid application, Serial No. 510,412. In either case the operation of the lamp is the same as respects the present invention. Moreover, as respects some features of the invention, it is not always necessary that the incandescent filament and the arc be operated in separate chambers. 40

It will accordingly be understood that the invention is not restricted to the several embodiments thereof which have been described and illustrated in the drawings, but is capable of a variety of physical expressions. Moreover, changes may be made in the details of construction and arrangement of the parts without departing from the spirit of the invention. Thus the lamp may have any desired size and shape and may be of any desired type, the electrodes may have any suitable form, the arc atmosphere may be of any suitable material depending upon the radiation which is to be produced, etc. Reference is therefore to be had to the appended claims for a definition of the limits of the invention. 55

What is claimed is:

1. An electric lamp comprising a pair of terminals, a plurality of filaments in said lamp and connected in series across said terminals, a pair of arc electrodes connected to said series circuit at points of different potential, at least one of said filaments being in series with said arc electrodes 60 and at least one other being in parallel therewith, and a resistance connected in series between one of said electrodes and its point of connection to said series circuit so as to lie in series with one of said filaments and in parallel with another. 65

2. An electric lamp comprising a pair of terminals, a plurality of resistances connected in series across said terminals and including at least one incandescent filament, a pair of arc electrodes connected to said series circuit at points of dif- 75

5. An electric lamp comprising a pair of terminals, a plurality of resistances connected in series across said terminals and including at least one incandescent filament, a pair of arc electrodes connected to said series circuit at points of different potential, at least one of said resistances being in series with said arc electrodes and at least one other being in parallel with said electrodes and including means for heating the electrodes, and an additional resistance connected in series between one of said electrodes and its point of connection to said series circuit. 5
10. An electric lamp comprising a pair of terminals, resistance means within the lamp and permanently connected across said terminals, a pair of arc electrodes connected to said resistance means at points of different potential, the arc path between said electrodes being in parallel with one portion of said resistance means and in series with another portion, and an additional resistance connected in series between one of said electrodes and its point of connection to said resistance means, said last named resistance being of a material which becomes incandescent 15 during normal operation of the arc. 10
15. An electric lamp comprising a pair of terminals, a bulb, means in said bulb providing separate chambers therein, a plurality of filaments connected in series across said terminals, a pair of arc electrodes connected to said series circuit at points of different potential and enclosed in one of said chambers, at least one of said filaments being in series with said arc electrodes and enclosed in another of said chambers and at least one other filament being in parallel therewith, and a resistance connected in series 20 between one of said electrodes and its point of connection to said series circuit. 20
20. An electric lamp comprising a pair of terminals, a plurality of resistances connected in series across said terminals and including at least one incandescent filament, a pair of arc electrodes connected to said series circuit at points of different potential, at least one of said resistances being in series with said arc electrodes and at least one other being in parallel with said electrodes and including means for heating the electrodes, means dividing the interior of said lamp into separate chambers, said arc electrodes and heating means being enclosed in one chamber, the resistance in series with the electrodes being enclosed in another chamber, and an additional resistance connected in series 25 between one of said electrodes and its point of connection to said series circuit. 25
25. An electric lamp comprising a pair of terminals, a plurality of resistances connected in series across said terminals and including at least one incandescent filament, a pair of arc electrodes connected to said series circuit at points of different potential, at least one of said resistances being in series with said arc electrodes and at least one other being in parallel with said electrodes and including means for heating the electrodes, and an additional resistance connected in series between one of said electrodes and its point of connection to said series circuit, said last named resistance constituting an incandescent filament. 30
30. An electric lamp comprising an outer bulb, a closed inner bulb, a pair of lamp terminals, an incandescent filament in said outer bulb, a pair of arc electrodes in said inner bulb, means for heating said electrodes, said filament and heating means being connected in series across the lamp terminals and said arc electrodes being connected to opposite ends of said heating means, and a resistance interposed between one of said electrodes and its point of connection to said heating means. 35
35. An electric lamp comprising a bulb, a pair of lamp terminals, resistance means permanently connected across said terminals in a series circuit and comprising a pair of heating filaments and an incandescent filament connected in series theretwixt, a pair of arc electrodes adapted to be heated by said heating filaments, connections from each arc electrode to said series circuit, and a resistance interposed in one of said connections. 40
40. An electric lamp comprising a bulb, a pair of lamp terminals, resistance means permanently connected across said terminals in a series circuit and comprising a pair of heating filaments and an incandescent filament connected in series theretwixt, a pair of arc electrodes adapted to be heated by said heating filaments, means in said lamp providing separate chambers, said incandescent filament being disposed in one of said chambers and said arc electrodes 45 in another chamber, connections from each arc electrode to said series circuit, and a resistance interposed in one of said connections. 45

GEORGE SPERTI. 50
